AUTOMATIC MULTIPLE COLOR PRINTING
PLATE AND INKING MEANS

William H. Hancock, Los Angeles, Calif.

Application November 13, 1945, Serial No. 628,223

14 Claims. (Cl. 101—201)

1

My invention relates to improvements in automatic multiple color printing plate and inking means, and more particularly to an automatically operated flat plate type, designed to provide a composite multiple color printing plate, operable upon a bed and platen press.

The several objects of this invention are: First, to provide a practical and simple composite printing plate, which in coaction with an associated operating means, a plurality of type compositions or cuts are provided with means to be inked in several colors, thereby; providing a flat bed printing press with means to print a plurality of colors, simultaneously from one impression of the plate.

Second, to provide a suitable mechanism to mount and operate a plurality of groups of standard ink rollers, in coaction with the movement of the parts of the composite printing plate, therefore; providing means to ink the plurality of printing elements comprising the type face of the printing plate; with a plurality of colors.

Third, to provide a coordinated printing mechanism which assures perfect registry of a plurality of colors in unlimited printing operation, and further; provides an improved printing plate assuring considerable economy in operating cost.

Fourth, to provide an improved mounting means, to mount a plurality of type compositions or cuts. Said means comprised of a plurality of parallel metal strips, or strips, of other suitable material of a suitable varying thickness and width, contriving and providing a simple means to mount and operate said printing elements, of various composition and varying width, in a multiple color printing plate, with said mounting strips provided with apertures and contact lugs at opposed ends, or at suitable intervals, providing means for selective operation of said mounting strips and affixed printing elements.

The foregoing and other objects of my invention will be clarified in the following specification and accompanying drawings in which:

Figure 1 is a perspective view of a press adapted to mount and operate the present invention.

Figure 2 is a section from line 2—2 on Figure 1, showing the printing plate in relation to the inking rollers and operating means.

Figure 3 is a fragmentary section from line 3—3 on Figure 2, showing an arrangement of the printing plate and operating bars in relation to an acceptable operating means, comprised of cylinder motors.

Figure 4 is a fragmentary section taken from line 4—4 on Figure 2, showing a view of an ink

2

roller carrier in conjunction with an acceptable operating means.

Figure 5 is a side view of the press adapted to mount and operate the present invention, showing an alternate means to operate the ink rollers and their carrier mechanism, illustrating rocker arms and the complementary motive means for said rocker arms.

Figure 6 taken from line 6—6 on Figure 5, as both sides of the press are typical, only one side is shown.

Figure 7 is a section taken from line 7—7 on Figure 5, clarifying the position of operating cams and gears.

15 Figure 8 is a view comprised of the view shown in Figure 3, changed to show an alternate method comprised of cams and shaft; providing another acceptable method to operate the printing plate operating bars.

20 Figure 9 is a fragmentary view taken from line 9—9 on Figure 8, showing a top view of the operating bars and cam shaft.

Figure 10 is a fragmentary view taken from line 10—10 on Figure 3, with the position altered approximately 20 degrees to show a perspective view of a section of the printing plate.

Figure 11 is a perspective of an unassembled part shown in Figure 10.

Figure 12, showing the detail of another part shown in Figure 10.

Figure 13, the third part in detail from the Figure 10 assembly.

Figure 14, the fourth and last part as shown in Figure 10 assembly.

35 Figure 15 is a fragmentary view showing both ends and other sections of the part 41c illustrated in Figure 12.

Figure 16 is a fragmentary view taken from line 16—16 on Figure 10, showing the arrangement of the supporting strips and affixed type.

Figure 17 is a fragmentary side view, taken as seen from the end of one group of the ink roller assemblies and is intended to clarify certain functions of the inking operation.

45 Figure 18 is a fragmentary view taken from line 18—18 on Figure 17.

Figure 19 is a fragmentary view taken from line 19—19 on Figure 18, this figure in conjunction with Figures 17 and 18 clarify the mechanism designed to correct the position of the offset ink rollers, and cause them to be forced over to pass along the inking plane.

Figure 20 is a partial phantom perspective, intended to further clarify the ink roller carriers and changeover mechanism.

55

Figure 21 is a fragmentary section from line 21—21 on Figure 19.

Figure 22 is a perspective of the casting comprising the major support of an ink roller carrier assembly.

Figure 23 is an unassembled fragmentary view of the swiveling carrier and attach means, between the ink rollers and roller carrier assemblies.

Brief description of purpose

My invention, comprising a multiple color printing plate and inking means, is designed to be flexible and adaptable to several presses and various motive means. Two tentative adaptations are illustrated herewith in Figs 1 and 5. Referring to Figures 1, 2, 3, and 4, frame 1 mounts the essential mechanism for a fully automatic press; comprising cylinder motors 5 which operates the ink roller carriers. Cylinder motors 42 which operates the printing plate parts. Cylinder motors 106 and 109 operating the web 105 paper feed from the supply roll 103. This described cylinder motor operated mechanism can be controlled by cam operated valves, operating upon a common shaft within the box 4 and with said common shaft motivated by an electric motor 102.

A secondary operating means are illustrated in Figures 5, 6 and 7, showing a cam and rocker arm method of operation of the inking rollers. Operating means comprising connecting rods 13 and 14, connecting to the ink roller carriers 1 by means of the lug shafts 97 and bearings 15, and with the said connecting rods affixed to the rocker arms 69, 70, 71 and 72, which are suitably mounted upon shafts 78, which are supported by bearings 79 and operated by cams 93 and 94, which are mounted upon shafts 95, which are suitably driven from the press operating means by the shafts 82 and 83 and gears 81, 84 and 85 and with said shafts and gears and bearings supported by the brackets 80 and 89. Said brackets comprising supports for bearings 86, 87, 88 and 96.

Referring to Figures 8 and 9, illustrating a shaft 61 and cam 62 operation of the printing plate operating bars 43, in conjunction with recovery springs 66 mounted 64 and 68 upon the back plate 3, and attached to the bars 43 by means of the rods 67 and heads 68, shafts 61 and cams 62 are timed and operated in conjunction with the press mechanism.

The foregoing described mechanism is outlined merely to illustrate the adaptability of my invention, and is not claimed or intended to be definite means of operation of my invention.

The printing plate

My invention comprises a support and operating means for a composite printing surface 53, in which a plurality of printing elements 53A, B, C and D comprising said printing surface. My invention provides means to individually ink said elements, in different colors, by projecting them individually beyond the printing plane 59 (see Figure 16), to a common inking plane 58 and applying rollers 22 which bear ink of the desired color. The desired projection of the said elements 53A, B, C and D are accomplished by affixing said elements to a plurality of back supports 41, by means of a dovetail joint 54 or other suitable affixation. Back supports 41 are comprised of the strips 41A, B, C, D and E, arranged in parallel order, horizontal to the printing plane.

Strips 41 are pierced at opposed ends or at

suitable intervals by apertures 56, with said apertures providing a matched passage, vertically, through the plurality of horizontal strips 41.

The apertures 56 are obstructed by the lugs 55A, B, C and D in staggered positions, said lugs comprise a projection into the apertures 56 from the strips 41 with the projection following A, B, C and D order as illustrated in Figures 11, 12, 13 and 14; so that printing elements 53A are controlled only by pressure lugs 55A, by means of movement of the operating bars 43A. With said movement transmitted to said printing elements by movement of the supporting strips 41A and 41AB, (see Fig. 11). The apertures 56 are provided with clearance, to allow individual movement of operating bars 43A, B, C and D in the order outlined, or in other sequences, therefore; element 53A would be operated by common movement of the operating bars 43A, lugs 55A and supporting strips 41A and 41AB.

The printing elements 53B, C, and D are controlled by like connection and movement of the other operating bars and supporting strips in the desired sequence, as in the illustrated movement of element 53C, (see Fig. 10) by supporting strip 43C, lugs 55C and operating bar 43C.

The supporting strips 41 comprise a suitable mounting means for all printing elements regardless of shape, by provision of the mounting arrangement. The varying thickness of the supporting strips 41, adapt to printing elements of varying sizes. Whenever one strip does not provide a suitable means to mount, provision of two or more strips as shown in Figure 11, provide a suitable support for printing elements extending beyond the edge of other printing elements. Unrestricted motion, and independent motion, of all printing elements are provided by slots 57, cut into the face edge of strips 41, the required depth to provide clearance for forward motion to all strips 41 (see Figure 15). The operation of the supporting strips 41 by the operating bars 43 are provided by insertion of a plurality of operating bars 43, through the apertures 56; which are aligned as hitherto described. Therefore, the operating bars 43 are inserted, vertically through the aligned apertures 56, and extend beyond the supporting strips 41 at top and bottom of the assembly, a predetermined distance, providing suitable connection with an operating means, consisting of revolving cams or other suitable propulsion. To maintain position in the apertures, pins 117 intersect the bars 43 at the upper and lower borders of the supporting strips 41 assembly. To maintain position of the printing plate assembly, brackets 116 placed at the top and bottom borders of the strips 41, are secured upon the face of the supporting back face plate 60. Printing position of the composite printing plate is provided by the ground and matched face plate 60, which is a part or surface of the support bracket 3, thereby; providing a rest for the matched back edges of the supporting strips 41, which are held locked thereon by the counter action of the operating bars 43. Alignment and registry of colors deposited upon the printing elements 53, are assured by the interlocking placement of said printing elements, which allows only the desired back and forth movement to said printing elements. To contrive a duplication of patterns across the surface of the printing plate, is provided by the slots 57 (see Figure 15), which provides underpass beyond intervening parts.

The inking device

75 Applying ink to the plurality of printing ele-

ments affixed upon my composite printing plate invention is accomplished by operating a plurality of ordinary inking rollers 22, up and down in proximity to the printing surface of the plate in the usual manner. To more satisfactorily adapt said rollers to proper coaction with the said printing elements upon a common inking plane 58, I have invented certain control means as hereinafter described. To provide rests for the supporting friction rollers 21, the tracks 23 and 24 are provided; said tracks are parallel in the vicinity of the printing plate, but are parted V-shaped above and below the printing plate. Providing clearance for the roller assemblies while at rest. To provide support and flexibility of movement to the inking rollers, the cast brackets 7 provide mounting means for a mechanism designed to be slidable horizontally, to control and support such movement of the said inking rollers 22. To provide vertical slidable movement and support for said brackets 7, sleeve bearings 31 are provided with apertures 38 which are intersected by the vertical rods 35, thereby; providing guides and vertical slidable mounting for said brackets 7. Rods 35 are securely affixed at top and bottom, to the frame 1 by means of the attach brackets 49 and 92. Brackets 7 are further provided with protrusions 32 and 48, providing means to attach said support brackets 7 to a suitable motive means.

To assure even pressure and flexible movement of the two grouped inking rollers 22, mounting means are provided by the swivel part 18 which are provided with bearings 19; to support the inking roller 22 shafts 20. Extending outward from the swiveling part 18, is a lug shaft 17, supported by bearings 16 provided in the sliding heads 11. Which moves and are supported in the bearing surface 12, provided in the slidable bracket 7. Said sliding head 11 is a part of the control rod 8, which are contained by bearings 13 and 15 in bracket 7. To exert pressure upon the control rod 8, the compression spring 9 is slipped upon the rod 8 and housed within the opening 14 in part 7. Said spring 9 is confined by the lip of the bearing 13 and the sleeve 36 which is pin 37 affixed upon the control rod 8. Therefore, it is apparent the pressure of the spring 9 is flexibly transmitted to the rollers 22, supporting friction rollers 21, by means of the described mechanism. Said pressure is absorbed upon the tracks 23 and 24. The bearing surfaces within brackets 7, provide horizontal support and sliding movement to the inking rollers and roller carriers.

It is apparent, that if the inking roller assemblies supported by tracks 24 should follow the normal course of said tracks, the desired contact of said ink rollers and printing plate surface would not occur. To correct this discrepancy, I have provided the lift tracks 28; which are affixed in a proper position upon the frame 1 outside and parallel to the tracks 24. Upon the roller carrier assemblies using track 24, are provided the special friction rollers 27, secured upon the lug shaft 26 by means of the washer 29 and cotter pin 30. Lug shaft 26 extends inward from the sliding head 25, which is contained in assembly by the bearing surface 12. Sliding head 25 is pierced by an aperture allowing passage of the rod 8. A coiled compression spring 10 is placed upon the rod 8 between the sliding heads 25 and 11. The movement, or transfer of the friction rollers 21 from tracks 24 to the desired position upon tracks 23, is accomplished by engagement of the friction rollers 27 upon the lift tracks 28.

Tracks 28, provided with curved ends, are mounted so that contact of rollers 27 upon the curved ends of track 28 cause outward pressure upon rollers 27. It is apparent that assembled 5 described, outward pressure upon the rollers 27 cause a lift and pressure upon the sliding head 25. Said lift and pressure is transmitted flexibly through the spring 10 to the sliding head 11. While said pressure is exerted, the passage of the 10 friction rollers 21 is disrupted from the track 24 and the assembly is forced forward, until the said friction rollers 21 are engaged by the tracks 23. Correcting the position of the inking rollers 22, causing them to pass along the common 15 inking plane 58. Predetermined tension must be provided for springs 9 and 10, to allow the described transfer of position.

Summary

20 Those skilled in the art, will appreciate the economy of applying a plurality of colors simultaneously, as printed by my composite printing plate. It is obvious from the specification, that 25 perfectly registered multiple color printing can be produced very rapidly and economically, with my composite printing plate and inking means. Although the forgoing specification describes the present invention as a four color plate, it is 30 readily seen that with modifications, my device is adaptable to two, three or more than four colors with the same expediency.

Further economy can be realized by quick removal of one composite plate and the substitution 35 of another, without the slow setup necessary in the present multiple color printing methods.

The nature of my composite support structure allows very close mingling of the several colors, provided by means of very thin supporting strips, 40 which allows very small cuts to be mounted in close relation to larger cuts; in the printing composition. Of course, many modifications of structural detail may be resorted to without departing from the scope of the invention, therefore; 45 I do not wish to be limited to the precise structure described, but consider my invention to include all modifications falling within the scope of the invention. I am aware that prior to my invention, multiple color printing plates 50 have been made with several means provided for multiple color printing, therefore; I do not claim such a combination broadly; but having described my invention, what I claim as new and desire to secure by Letters Patent is:

55 1. A multiple color printing plate comprising a movable type base, comprised of a plurality of parallel movable strips providing means to mount a plurality of printing elements, with said parallel movable mounting strips, horizontally opposed to 60 a vertically operated inking means, and with said parallel strips provided with clearance slots and clearance apertures, with said apertures provided with inwardly extending contact lugs and with said lugs upon separate strips, staggered, providing 65 selective contact with operating means intersecting said apertures, providing means to contact said plurality of affixed printing elements with selective inking means.

2. A multiple color printing plate comprising a 70 plurality of printing elements, affixed to a composite movable base comprised of a plurality of parallel supporting strips, comprising slots and apertures, with said apertures provided with inwardly extending lugs, providing means to contact operating means provided to move said sup-

ported printing elements outward, selectively to a common inking plane.

3. In a multiple color printing plate, comprising a plurality of printing elements affixed to a composite movable base, comprised of parallel movable strips of varying thickness, providing means to mount printing elements of varying sizes and with means provided to move said supported elements outward to a common inking plane.

4. In a multiple color printing plate, comprising a plurality of printing elements affixed to a composite movable base, comprised of parallel movable strips of varying thickness, and with printing elements of large size affixed to a plurality of supporting parallel strips, suitably placed in relation to the assembly, with means provided to move said supported elements outward to a common inking plane.

5. A multiple color printing plate substantially as claimed in claim 4, wherein all the supporting strips are provided with clearance slots to facilitate selective movement of said printing elements, outward to a common inking plane.

6. A multiple color printing plate comprising a plurality of printing elements, affixed to a plurality of parallel strips, provided with varying thickness to support variable sized printing elements and with printing elements not adapted to support from one strip, being provided with a plurality of supporting strips spaced as required in the assembly and with all strips provided with clearance slots to facilitate selective movement and with all strips provided with a sufficient uniform width to provide cantilever strength and with said assembled strips pierced by apertures and with said apertures comprising a common aperture through the assembly, at opposed ends or at intervals as required, providing means to insert a plurality of parallel operating bars within said apertures and with means provided to contact said operating bars with selective groups of said parallel supporting strips.

7. In a multiple printing plate, the combination described in claim 6, wherein said strips are provided with apertures for the insertion of operating bars and wherein said operating bars are provided with selective contact means with the said supporting strips, said selective means comprising lugs in staggered order extending inward from the said supporting strips into the said apertures and with the apertures provided with clearance space whereby certain operating bars contact selected lugs and bypass other lugs, thereby; providing selective operation of the said strips and affixed printing elements and providing movement of said printing elements outward in sequence, to a common inking plane to provide coaction with inking rollers applying selected colors thereto.

8. In a multiple color printing plate, a composite base comprising a plurality of parallel movable strips, provided with a plurality of affixed printing elements and with said supporting strips provided with clearance slots and clearance apertures, with said apertures provided with contact lugs, providing means of contact with operating means and with the said parallel supporting strips provided with matched rear edges comprising a uniform rest means, the combination of a supporting rest means comprising brackets and a support bracket, provided with a suitable ground and matched surface to provide alignment of said parallel support strips and affixed printing elements while at rest in printing position.

9. In a multiple color printing plate, comprising a plurality of printing elements affixed to a composite movable base, comprised of a plurality of parallel supporting strips and with means provided to move said supported printing elements outward, selectively, to a common inking plane, the combination of inking means comprising a plurality of inking roller groups provided with carrier and corrector means to provide coaction with said selective printing elements on a common inking plane.

10. In an inking device comprising a plurality of inking rollers mounted above and below a multiple color printing plate, with means provided to move said inking rollers over a common inking plane in coaction with selective movement of printing elements in said printing plate and with said inking rollers provided with mounting means comprising a swivel mount with a central connector and with said connector provided with slidable support comprising sliding heads and guide rods, a support, vertically mounted and slidable vertically, provided with support means comprising horizontal slide bearings, providing mounts for said sliding heads and guide rods, thereby; providing horizontal motion means for said affixed inking rollers and with retainer compression springs comprising means to retain said assembly upon support tracks.

11. In an inking device, the combination described in claim 10, a vertically disposed bracket provided with means to move vertically, with said bracket providing horizontal slide means to support inking roller carrier means.

12. In an inking device, comprising a plurality of inking rollers intended to operate in sequence, comprising friction rollers and supporting tracks, a control means comprising a swiveling support with bearings and center swiveling means, a support comprising a vertically supported slidable bracket provided with horizontal bearing surfaces, comprising an elongated slide means providing support, a sliding head and a guide rod, with guide means within said horizontal disposed bearing surfaces, retainers, comprising a compression spring disposed about said guide rod and retained thereon by means of sleeve and pin retention.

13. In an inking device, comprising a plurality of inking rollers grouped above and below a printing plate, a plurality of parallel tracks providing a support for said inking rollers, an offset track providing means to cause said inking rollers to coact upon a common inking plane, said means comprising said offset track, coacting with a friction roller mounted upon a sliding head, slidable in a common carrier in conjunction with a sliding head and a guide rod, a compression spring confined between said sliding heads, providing means to transmit pressure upon a flexible mounting means of said inking rollers, said coaction of tracks, rollers, and sliding heads, providing correcting means to said inking rollers.

14. In an inking device, the combination described in claim 13, comprising inking rollers supported upon parallel tracks, corrector means, comprising lift tracks affixed in juxtaposition to said parallel tracks, said lift tracks provided with curved ends, corrector means, comprising friction rollers affixed in position to engage the curved ends of said lift tracks, and with said friction rollers affixed to said inking roller carriers, a lug shaft affixed to a slidable head, horizontally disposed within common support means, said head provided with an aperture comprising

insertion means for a guide rod, said guide rod provided with a sliding head, a compression spring disposed about said guide rod, said compression spring confined between said slidable heads so that pressure upon the first mentioned 5 slidable head is flexibly transmitted to the second slidable head, whereby horizontal motion is applied upon the inking roller assembly supported by the second mentioned slidable head, providing means to correct the position of the 10 said inking rollers.
